UNITED STATES PATENT OFFICE.

ALBERT BACON PRATT, OF LYNDON, VERMONT; DAVID E. PORTER ADMINISTRATOR
OF SAID ALBERT B. PRATT, DECEASED.

FIREARM.

Application filed June 22, 1917. Serial No. 176,367.

To all whom it may concern.

Be it known that I, ALBERT BACON PRATT, a citizen of the United States, and a resident of Lyndon, in the county of Caledonia and 5 State of Vermont, have invented a new and Improved Firearm, of which the following is a full, clear, and exact description.

The invention relates to firearms, such as shown and described in the Letters Patent 10 of the United States, No. 1,191,460, granted to me on July 18, 1916.

The object of the present invention is to provide a new and improved firearm arranged to insure accurate shooting at any 15 range up to the limit distance without requiring any material change in the position of the firearm relative to the hands, face, arms, shoulders and eyes of the marksman. Another object is to enable the marksman to 20 quickly find and to aline the front and rear sights. Another object is to enable the marksman to firmly hold the firearm in position with a view to prevent rolling action of the firearm while taking aim.

In order to accomplish the desired result 25 use is made of a firearm provided with a stationary rear sight and an adjustable front sight for varying the elevation of the firearm relative to the range.

A practical embodiment of the invention 30 is represented in the accompanying drawings forming a part of this specification, in which similar characters of reference indicate corresponding parts in all the views.

Figure 1 is a side elevation of the firearm; 35 Figure 2 is an enlarged cross section of the same on the line 2-2 of Figure 1 and showing more particularly the rear sight, parts of which are shown broken out;

Figure 3 is a side elevation of the rear 40 sight in position on the barrel;

Figure 4 is a longitudinal central section of the same on the line 4-4 of Figure 5;

Figure 5 is a rear face view of the rear 45 sight in position on the firearm, part of which is shown in section;

Figure 6 is a sectional side elevation of the removable pistol grip in position on the main stock;

Figure 7 is an enlarged side elevation of the front end of the barrel provided with the front sight and the bayonet holder;

Figure 8 is an inverted plan view of the same;

Figure 9 is a longitudinal central section 55 of the front sight in position on the barrel;

Figure 10 is a cross section of the same on the line 10-10 of Figure 7;

Figure 11 is a similar view of the same on the line 11-11 of Figure 7;

Figure 12 is a perspective view of one of the clamping members for clamping the rear sight in the adjusted position; and

Figure 13 is a cross section of the barrel 60 on the line 13-13 of Figure 7, and showing 65 the bayonet holder in elevation.

Rifles and similar firearms as heretofore constructed are provided with a vertically adjustable rear sight and a stationary front sight. For adjusting the firearm to different ranges it is necessary to correspondingly raise or lower the rear sight, but in doing so a corresponding change of the holding position of the firearm relative to the marksman's body is necessary, hence it is evident 75 that changing of positions renders the obtaining of the proper aim very difficult especially when the range exceeds, say, 200 yards. A further disadvantage is that when attempting to aim, a rolling action is given 80 to the firearm incident to the shape and angle of the drop of the stock, and inaccurate shooting is the result. With my improvement presently to be described in detail, the firearm is held practically in the same position for the different ranges and accurate 85 and quick sighting can be had for any range by making the rear sight permanent and the front sight adjustable in an up and down direction when held in horizontal position by 90 the pistol grip.

The firearm shown in Figure 1 consists essentially of a barrel 20, a firing mechanism 21 of usual construction, and a mainstock 22 terminating in a butt stock or a shoulder 95 piece 23 having its upper edge inclined forwardly and downwardly from the heel 24 to the comb 25, and with the axis of the barrel 20 approximately intersecting the heel 24, as plainly indicated in Figure 1. The 100 thumb recess 26 is arranged in front of the comb 25 and located opposite a removable pistol grip 27 hereinafter more fully described.

The firearm is provided with a stationary rear sight 30 and a vertically adjustable front sight 31. The rear sight 30 is located on the firearm at any convenient point between the shooter's eye and the muzzle sight 31 either on the stock, frame, barrel or firing pin. By elevating the heel 24 relative to the axis of the barrel 20 and providing a permanent rear sight 30 and a vertically adjustable front sight 31 the marksman is enabled to hold the firearm practically in the same position when firing at a short or a long range up to the limited distance of the firearm. It is understood that the vision of the marksman is changed comparatively little owing to the combined arrangement of the butt stock 23, the permanent rear sight 30 and the adjustable front sight 31.

The rear sight 30 is preferably constructed as follows, special reference being had to Figures 2, 3, 4 and 5: A carrier 32 is provided with lugs 33 engaging a transverse pivot 34 held in a saddle 35 screwed or otherwise secured to the top of the rear end of the barrel 20. The carrier 32 at its rear face is provided with a transversely extending dovetail tongue 36 engaged by a dovetail groove 37 formed on the front face of the rear sighting piece 38 provided on the top with the usual sighting notch 39 and on the front with a center indicating line 40 leading to the center of the notch 39, as plainly shown in Figure 5. On the rear face of the sighting piece 38 is pivoted at 45 a peep sight 46 having a peep opening 47 adapted to register with the notch 39 at the time the peep sight 46 is swung upward from normal inactive lowermost position into uppermost active position, as indicated in Figure 4. The peep sight 46 is provided at its pivotal end with a square heel 48 pressed on by a spring 49 to hold the peep sight 46 firmly in either lowermost inactive or in uppermost active position, as above explained.

In order to provide the desired windage use is made of a screw 50 mounted to turn on a transverse shaft 51 journaled in the sides of the sight carriage 32 and the said screw engages screw threads 52 formed on the face of the sighting piece 38 so that when the screw is turned a corresponding sidewise shifting of the sighting piece 38 takes place to compensate for the force of the wind prevailing at the time. The screw 50 extends within a recess 53 formed in the carrier 32, as plainly shown in Figure 4, and the said screw is protected by a locking cover or hood 54 pivoted at 55 on the sides of the carrier 32. The cover 54 is provided at its sides with extensions 56 (see Figure 3) normally engaging the sides of the sighting piece 38 at the time the latter is in central position on the carrier 32, so that the sighting piece 38 is locked against transverse movement.

When it is desired to shift the sighting piece

38 transversely for windage, as previously mentioned, then it is necessary for the marksman to swing the cover 54 upward into the position shown in dotted lines in Figure 3, to disengage the side extensions 56 from the sides of the sighting piece 38 to allow shifting of the latter in a transverse direction on turning the screw 50 correspondingly. It will be noticed that when the cover 54 is in closed position the screw 50 is out of reach of the marksman and consequently cannot be accidentally turned.

In order to hold the rear sight 30 in vertical active position or in folded horizontal position use is made of locking pins 60 mounted to slide in the under side of the carrier 32 and pressed on by springs 61 (see Figure 5). The lower ends of the locking pins 60 are adapted to engage recesses 62 formed in the top of the saddle 35 to hold the carrier 32 in vertical active position, as illustrated in Figures 2, 3, 4 and 5. The rear sight 30 is adapted to be swung forward into horizontal position and when this position is reached the pins 60 engage recesses 63 formed in the front face of the saddle 35 (see Figure 2) to hold the front sight locked in this folded position.

The front sight 31 is constructed as follows, special reference being had to Figures 7, 8, 9, 10, 11 and 12: On the front end of the barrel 20 is fastened a sleeve 70 by means of a key 71 (see Figures 9, 10 and 11) and at the rear upper portion of the sleeve 70 are arranged transversely extending pivots 72 on which is mounted to swing up and down a front sighting piece 73 having segmental side arms 74 connected with each other by a cross plate 75. On the forward end of the cross piece 75 is secured a base 76 provided on top with a sighting rib 77 and extending longitudinally in a vertical plane passing through the axis of the barrel 20. The rib 77 is curved, as plainly shown in Figure 9, so that the top of the ridge forms a sighting edge in any position the sighting piece 73 may be swung into, that is, up or down according to the range. The sighting rib 77 is flanked by cheeks 78 to protect the sighting rib against sidewise glare and to permit the marksman to more quickly find the rib 77 when sighting. The sighting rib 77 as well as the cheeks 78 form integral parts of the base 76 and the base is shrunk or otherwise firmly secured to the cross plate 75 of the sighting piece 73. In order to prevent top glare reaching the sighting rib 77 use is made of a hood 80 pivoted at 81 on the side arms 74 and adapted to be swung up into vertical position across the top of the cheeks 78 and the sighting rib 77, as indicated in dotted lines in Figure 7. Normally the hood 80, however, is in lowermost position with the lower edge of its crosspiece resting on the side arms 74 of the sighting piece 73. Each

of the side arms 74 is provided on its outer face with a distance graduation 85 representing yards or other similar unit measurement. The marginal portions of the side arms 74 are engaged at their faces by flanges 86 forming integral parts of the front end of the sleeve 70. One of the flanges 86 is provided with a pointer 87 indicating the range on the corresponding mark of the graduation 85.

In order to lock the sighting piece 73 in the adjusted position, use is made of clamping members or shoes 90 engaging the peripheral edges of the side arms 74, and the said clamping shoes 90 are mounted in guideways formed between the sides of the sleeve 70 and the flanges 86, as plainly indicated in Figures 7 and 10. The lower ends of the clamping shoes 90 are mounted on eccentric trunnions 91 formed on the ends 20 of a shaft 92 extending transversely and journaled in the lower front portion of the sleeve 70 (see Figure 10). On the shaft 92 is secured a handle 93 extending normally rearwardly in an approximately horizontal position. The shaft 92 is provided with a flattened portion 94 (see Figures 9 and 10) engaged by the free end of a spring 95 secured by a screw or other fastening means 96 to the sleeve 70, as shown in Figure 9. The spring 95 normally holds the handle 93 in a horizontal position with the clamping shoes 90 in locking engagement with the peripheral edges of the side arms 74.

When it is desired to unlock the sighting piece 73 the marksman swings the handle 93 downwardly and forwardly to turn the shaft 92 to cause the eccentric trunnions 91 to move the shoes 90 out of clamping position relative to the peripheral edges of the side arms 74. The sighting piece 73 can now be swung up or down until the pointer 87 indicates the desired range on the corresponding mark of the graduation 85. The handle 93 is then swung backward and upward to its normal position to re-engage the clamping shoes 90 with the side arms 74 to lock the sighting piece 73 in the adjusted position. Each of the shoes 90 is preferably provided with an offset 97 adapted to bear 50 against the under side of the corresponding flange 86 to prevent any possible accidental movement of the shoes and to insure a proper clamping of the side arms 74.

On the barrel 20 immediately in the rear 55 of the front sight 31 is arranged a bayonet holder 100 depending from a bracket 101 having a base 102 provided with a dovetail groove 103 (see Figure 13) engaging a dovetail tongue 104 formed on the under side of a sleeve 105 secured to the barrel by a transverse pin 106. A set screw 107 serves to fasten the base 102 to the tongue 104 to securely hold the bracket in position on the sleeve 105. On the rear end of the bracket 60 65 101 is pivoted a strap loop 108 adapted to

be engaged by the carrying strap whenever such is used.

The pistol grip 27 is provided on top with a face plate 110 fitting on a similar plate 111 attached to the underside of the stock 22 70 and the latter is provided with a nut 112 screwed or otherwise fastened in the stock, as plainly indicated in Figure 6. In the nut 112 screws a screw 113 having a reduced portion 114 and extending in an opening 75 115 formed in the pistol grip 27. The reduced portion engages a bearing 116 screwed or otherwise secured in a recess in the bottom of the grip 27, and on the lower end of the reduced portion is formed a head 117 80 adapted to be taken hold of by the marksman for turning the screw 113 with a view to screw the screw in or out of the nut 112 whenever it is desired to fasten the pistol grip in place or remove it therefrom. The head 117 is preferably flush with the underside of the pistol grip 27 to present no undesirable projection and thus to allow taking convenient hold of the pistol grip whenever it is desired to do so. The pistol grip 27 90 is provided with a pin 120 arranged parallel to the screw 113 and in front of the same, the pin engaging a recess 121 formed in the stock to prevent the pistol grip 27 from accidental turning. 95

It is understood that I do not limit myself to the detail construction of the invention as shown and described, as the same may be varied without deviating from the spirit of my invention. 100

Having thus described my invention, I claim as new and desire to secure by Letters Patent:—

1. A shoulder-supported firearm comprising, in combination, a stock having a top portion closely adjacent a line passing through the axis of the barrel, a rear sight adjacent the breech of the gun and fixed against vertical movement, and a vertically adjustable front sight, whereby adjustment 105 of the sighting system for different ranges necessitates substantially no change in the position of the head of the marksman relative to the stock of the gun, and whereby the aim at all ranges is steadied by the cheek 110 115 of the marksman resting against the top portion of the stock.

2. A shoulder-supported firearm comprising, in combination, a stock having a top portion closely adjacent a line passing 120 through the axis of the barrel, said stock sloping downwardly from heel to comb, a rear sight adjacent the breech of the gun and fixed against vertical movement, and a vertically adjustable front sight, whereby 125 adjustment of the sighting system for different ranges necessitates substantially no change in the position of the head of the marksman relative to the stock of the gun, and whereby the aim at all ranges is steadied 130

by the cheek of the marksman resting against the top portion of the stock.

3. A firearm provided with a stock provided at the under side with an embedded nut and a recess spaced from the said nut, a pistol grip, a screw mounted to turn in the said pistol grip and screwing in the said

nut, and a pin on the said pistol grip engaging the said recess.
